VIBRATING TRICK TOY

Richard Appel, Sunnyside, Long Island, N. Y.

Application September 19, 1941, Serial No. 411,469

3 Claims. (Cl. 272—27)

It has been known to provide simulations of articles of common use as, for example, match boxes, with means releasable when the articles are lifted to set up a surprise vibration, the articles being known as "trick" matchboxes, etc.

The object of the present invention is to provide a construction of such devices, which employ a spring clockwork and to enable winding of the spring by a readily accessible thumbpiece having its top flush or substantially flush with a primary holding frame in such manner that it may readily be slid into the outer member of the standard box for wooden matches or any article casings having similar receiving apertures.

The invention will be described with reference to the accompanying drawing, in which:

Figure 1 is a view in sectional elevation, the section being taken longitudinally of the device as shown within the outer member of a customary safety match box, the horizontal line indicating the surface of the table or other support upon which the device rests.

Figure 1A is a fragmentary view in sectional elevation showing the right hand end of the structure illustrated in Figure 1 with a modified form of latch lever arrangement.

Figure 1B is a schematic view showing in dotted lines the lower plate 2 of the main frame and the modified latch lever carried thereby.

Figure 2 is a view similar to Figure 1, showing the article raised above the line representing a support and thus thrown into action.

Figure 3 is a bottom plan view, partly in section and partly in dotted lines, the section being taken on the line 3—3, Figure 1.

Figure 4 is a transverse sectional elevation on the line 4—4, Figure 1.

Figure 5 is an isometric view of the device reversely positioned to expose its lower face, the latter being normally concealed.

Figure 6 is an enlarged fragmentary sectional elevation, the section being taken on the line 6—6, Figure 7, the figure illustrating connected ends of the main and supplemental frames.

Figure 7 is a view in end elevation of the supplemental frame, showing its connection with the underlying main frame.

Figure 8 is an enlarged end fragmentary view in perspective of one of the two supplemental frame members.

Figure 9 is a view similar to Figure 8, illustrating the opposite end of said supplemental frame member.

The specific object of the invention is to provide a novel frame construction comprising a

primary frame member and a secondary frame constructed of two like interfitting sections connected to the primary frame member in such manner that the key winding element is projected within a flanged annular opening formed in the primary frame member and the bent outer end of the latch lever for the clock mechanism is positioned and guided within the flanged opening formed in the said primary frame member.

10 Referring to the drawing, I have indicated at 1 a common type of match box casing having the inner slide member 1x, the casing being apertured at a for access to the key winding element of the mechanism and apertured at a^x for passage of the bent end of the latch lever which controls said mechanism.

Within the slide member 1x of the match box casing is disposed the main frame member 2 which is formed as a rectangular plate bent at right angles at each end for a length equivalent to the inner width of the slidable box member 1x.

20 The main frame member is formed with a circular opening bounded by an inturned annular flange 2x and it also is formed with a second aperture 2xx, Figure 3, adapted to lie in register with the opening a^x of the box casing 1.

25 The main frame member 2 is formed, near each end, with a plurality of slots to receive short lugs 3x depending from each angularly extending end of a supplemental frame member 3, there being two of these supplemental frame members. After the lugs 3x are passed through the appropriate slot of the primary frame member, they are bent over in the manner shown in Figure 7. One end of each supplemental frame member may be formed as shown in Figure 8 and the opposite end as shown in Figure 9, the difference being that one of the two ends is formed with a slot at 3xx for a purpose hereinafter described. In Figures 8 and 9 the central of the three lugs 3x therein shown has not been bent to horizontal position as in Figure 7.

30 Near the top of each end portion of the supplemental frame members there is formed an integral strap projection 4 adapted to receive the central lug 3x of its complementary supplemental frame member. When two of the supplemental frame members are brought together in such manner the outermost lug of the uppermost supplemental frame member may be bent inwardly as shown in Figures 6 and 7. In such movement the outermost lugs of the top sup-

plemental frame member pass through clearances at the points *c*, Figures 8 and 9, and finally abut the underface top wall of the underlying supplemental frame member, thus latching the two members of the supplemental frame into firm connection. The two supplemental frame members are formed with aligned bearing apertures to receive three shafts. The first shaft, 4, is a shaft connected to the inner end of a spiral spring 5, the outer end of the spring being projected through an adjacent opening $3xx$ of one of the ends of the uppermost supplemental frame member. The shaft projects beyond the supplemental frame and carries a thumb winder 6 projected into the opening of the main frame bounded by circular flange $2x$, as shown in Figure 5. Shaft 4 also carries a drive gear 7 in mesh with a small pinion 8 on a shaft 9 which is the second shaft mounted in aligned apertures of the supplemental frame. The third set of aligned apertures in the supplemental frame receives a shaft 10 carrying a pinion 11 in mesh with a gear 12 carried by shaft 9. Shaft 10 carries an eccentrically arranged weight 13 which normally engages the inner end $14x$ of a lever 14 serving as a latch, the bent end of the lever being in opening a^x of the casing 1.

When the lever is in the position of Figure 2, said clock mechanism may operate to rapidly rotate eccentrically disposed weight 13 which will set up a vibration to the device as a whole. When the outer end of the latch lever is in the position of Figure 1, the end $14x$ thereof will be brought into such position that the weight 13 will engage the latch lever and rotation of weight 13 will be stopped. In such condition the thumb winding element 6 may be rotated to wind the spring. When the spring is wound, care being taken to hold the outer end of the lever in the position of Figure 1, the device may be placed upon the support, the latter being indicated by the horizontal line *s*, Figures 1 and 2, and the parts will remain at rest.

As soon as the device is lifted from the table or other support *s*, the latch lever will move by gravity to the position of Figure 2 and the device will set up a vibration.

By inwardly flanging the walls of the aperture, the main frame 2 through which the bent end of the lever passes, as shown at 15, Figures 2 and 4, the bent lever end is guided in its movement and any tendency for catching on the bottom of the primary frame is avoided. By forming the supplemental frame of like member adapted for mutual connection, each member may be made by operation of a single die. Due to the form of the device, it is very cheaply constructed and yet strong and rugged.

Figures 1A and 1B show a modified form of latch lever, 14a, which lever comprises a strip of metal formed with short intermediate wings *W*. Looking at Figure 1B it will be seen that when the lever is inserted into a slot a^{xx} formed in the main or primary frame member 2, the slot being of less width than the distance from end to end of its rectangular top section, said top section will lie on top of member 2 whilst the lower outwardly projected portion, which is of greater weight, will serve to rock the lever to the dotted line position of Figure 1A when the device is lifted from the table or other support. This insertion of the

latch lever will first require bending of the wings into parallelism so that they will pass through the slot, which will be slightly greater in width than the distance intermediate the wings. When the latch lever is thus inserted the wings will be bent back into straight line arrangement as shown. When the device is placed upon a support the lower end will be moved upward, thus causing the latch area to be moved in line with the eccentrically arranged weight 13 to latch the same. In a number of cases the main frame may be omitted and the device with such omission may be mounted in any suitable container as, for example, candy boxes, cigarette boxes, etc. Also a crank 15 may be substituted for the weight member 13.

Having described my invention, what I claim and desire to secure by Letters Patent, is as follows:

1. In a vibrating trick, a main frame comprising a plate formed with a circular opening, a supplemental frame carried by the main frame and comprising two like plates having angularly bent extensions at their ends, the plates being superposed and held in spaced relationship by said extensions, means carried by said extensions interlocking together, three shafts held in aligned bearing apertures of and between the plates of the supplemental frame, a spiral spring and drive gear on one shaft, a driven pinion and drive gear 20 on the second shaft, being an intermediate shaft, and a driven pinion on the third shaft, the said shaft-held members lying between the plates of the supplemental frame, a thumb winding element connected to the spring-holding shaft, said element being projected exteriorly of the plates 25 of the supplemental frame and into register with the circular opening of the main frame, an eccentric weight carried by the last of the said three shafts and projected exteriorly of the two plates 30 of the supplemental frame, and a latch lever for controlling the action of the spring, each angularly bent extension at an end of the two plates comprising the supplemental frame having a relatively narrow section directly connected to its 35 plate and carrying a strap open at its top, the narrow extension merging into a broader extension having a plurality of bendable lugs.

2. In devices of the character set forth a main frame and, a supplemental frame comprising two 40 like plates having angularly bent extensions at their ends, the plates being superposed and held in spaced relationship by said extensions, means carried by said extensions interlocking together, three shafts held in aligned bearing apertures of 45 and between the plates of the supplemental frame, a spiral spring and drive gear on one shaft, a driven pinion and drive gear on the second shaft, being an intermediate shaft, and a driven pinion on the third shaft, the said shaft-held 50 members lying between the plates of the supplemental frame, a thumb winding element connected to the spring-holding shaft, said element being projected exteriorly of the plates of the supplemental frame, an eccentric member carried 55 by the last of the said three shafts, and a latch device for engaging said eccentric member.

3. A device constructed in accordance with 60 claim 2, in which the latch device for the eccentric member comprises a strip of metal formed 65 with short intermediate wings.
